UNITED STATES PATENT OFFICE.

GEDOR W. ALDEEN, OF ROCKFORD, ILLINOIS, ASSIGNOR TO NATIONAL LOCK CO., OF ROCKFORD, ILLINOIS, A CORPORATION OF DELAWARE.

HINGE.

Application filed April 13, 1925. Serial No. 22,505.

My invention relates to hinges and particularly to the form of hinge which is used on a door outstanding slightly from the jamb such as refrigerator doors and where the leaves of the same must necessarily be out of alignment in order to provide for the full closing of the door. A refrigerator door offers a very good example for use of the type of hinge I have shown in my drawings as the door being required to fit snugly, the thickness of the overlapping marginal portion must be provided for in the extensions from the base portion to the leaf connected to the door. Various methods of providing for the hinge of the base portion and the leaf have been devised but one of the main objections to most forms of outstanding leaf hinges is the weakness of the hinge at the pivotal point which is compelled to bear the entire weight of the door and should therefore be of the strongest possible construction.

In my improved hinge I have provided a novel support for the lugs leading up from the punched out base portion which not only serve in such capacity but also improve the appearance of the said base portion by completely covering the same so as to give it the appearance of a single piece of finished metal.

In the drawings:

Fig. 1 shows a top and plan view of the hinge in its closed position;

Fig. 2 is a vertical sectional view on line 2—2 of Fig. 1;

Fig. 3 is a side elevation of the hinge in its closed position;

Fig. 4 is a modification of a lesser number of pivotal supporting lugs;

Fig. 5 is a cross sectional view on line 5—5 of Fig. 4;

Fig. 6 is the inner end portion of a blank leaf before use in the form of hinge shown in Fig. 6;

Fig. 7 shows another design of my improved hinge with a greater number of pivotal supporting lugs;

Fig. 8 is a vertical sectional view of the same on the line 8—8 of Fig. 7; and

Fig. 9 is a side elevation of the type of hinge shown in Fig. 7.

Like symbols of references herein indicate like parts in each of the figures of the drawing. As illustrated in the drawing, my improved hinge has a base portion

10 preferably stamped from sheet metal and the blank of which is so formed as to permit the end lugs 11 to be turned up at right angles therefrom to form a pivotal connection with the leaf member 12. Intermediate of the end lugs 11 there may be a center lug 13 or two lugs 14 as shown in Figs. 7 and 8 or in hinges of smaller construction the end lugs 11 may be sufficient for pivotal connection with the leaf member. This pivotal connection is formed by a pin 15 passing through the holes 16 in said lugs while the curls 17 on the leaf 12 pass around said pin and completely fill the spaces between the said lugs, except that the leaf 12 being provided with a downwardly extending flange 18 which is provided with an opening 19 in the same, is fixed between the outer portion of each of the curls shown in Figs. 1 and 2 and the inner side of the end lugs 11. By reference to Fig. 6, it will readily be seen that the end of the leaf member 12 is blanked out so that the outwardly extending portion 20 is merely turned under so as to provide the same with a curl while the downwardly extended flanges 18 are formed in such manner that the holes 16 therein are brought into alignment with the holes in the pivotal lugs and with the curl 17 formed on the inner end of said leaf so that when the outer ends of the pin 15 are riveted or otherwise secured therein, a firm and compact pivotal connection is formed. It will be evident that a certain amount of the strength of the base portion 10 has been taken away by striking up the pivotal lugs 11 and 13 as they are struck completely through the said base portion and leave the openings 22 in the same and to provide the necessary strength to the said base portion before securing the same to the leaf or placing the pin 15 therein, I place a cover plate 23 over the entire base portion and said cover plate is provided with slots 24 for permitting the passage of the pivotal lugs therethrough. The cover plate is provided with small downwardly extending flanges 25 completely around the outer edge of the same and the outer edge of these flanges are flush with the bottom of the base portion so that said cover plate completely encloses the said base portion. The holes 27 in the base portion are slightly countersunk and the cover plate is provided with slightly countersunk portions 28 thus giving a finished appear-

ance to the countersunk hole 27 in said plate.

As illustrated in the drawings, I do not limit myself to any particular number of pivotal lugs or curls for forming the pivotal connection between the body portion and the leaf member, but this will depend entirely upon the particular class of work for which the hinge is designed. Figure 1 shows a hinge having three pivotal lugs; Figures 4 and 6 show one having merely two end lugs while Figures 7 and 8 show a hinge provided with four pivotal lugs blanked out from and extending up from the base portion 10. Neither do I limit myself to any shape or design in the base portion 10 or the leaf member 12 and while I have shown two preferred designs in Figures 1 and 7, many other designs with suitable countersunk holes 30 for connecting to the door frame may be used.

It will therefore be seen that while providing a neat and finished appearance to the base portion of my improved hinge, the cover plate will also act in the more important capacity of securing, binding and stabilizing the pivotal lugs by the edges of the slots 24 in said plate engaging the sides

and ends of said lugs, whereby strength will be given to the hinge construction so that it will be possible with this form of hinge 30 to add additional weight to the leaf 12 without distorting or otherwise injuring the pivotal connection.

It is believed that the construction and many of the attendant advantages of this invention will be apparent from the foregoing without further description and while I have shown and described three preferred embodiments of my invention, obviously the structural details and design are capable 40 of wide variation without exceeding the scope of the invention as defined in the following claim.

I claim:

A hinge comprising a leaf plate having 45 a plurality of pintle supporting lugs struck up therefrom, one of said lugs leaving a corresponding aperture in the plate, a strengthening cover plate fitted over said leaf plate covering said aperture and 50 strengthening said lugs, a pintle supported by said lugs and a second leaf plate pivoted to said pintle.

GEDOR W. ALDEEN.
